UNITED STATES PATENT OFFICE.

PRESLEY B. JOHNSON, OF SACRAMENTO, CALIFORNIA.

SEAL-LOCK.

1,093,135.

Specification of Letters Patent. Patented Apr. 14, 1914.

Application filed October 17, 1913. Serial No. 795,737.

To all whom it may concern:

Be it known that I, PRESLEY B. JOHNSON, a citizen of the United States, residing at Sacramento, in the county of Sacramento and State of California, have invented certain new and useful Improvements in Seal-Locks; and I do hereby declare the following to be a full, clear, and exact description of the invention, such as will enable others skilled in the art to which it appertains to make and use the same.

This invention relates to seal locks and seals especially adapted for use on cars, and has for one of its objects to provide a seal lock from which it is absolutely impossible to detach the seal without breaking the latter.

Another object of the invention is to provide a seal lock including a casing, a rotary member housed within said casing and provided with means for attachment with the seal, and means for preventing a rotation of the rotary member in one direction.

A further object of the invention is to provide a novel form of seal especially adapted for use with my improved lock.

With these and other objects in view as will become more apparent as the description proceeds, the invention consists in certain novel features of construction, combination and arrangement of parts as will be herein-after more fully described and claimed.

For a complete understanding of my invention, reference is to be had to the following description and accompanying drawings, in which—

Figure 1 is a perspective view of the lock and seal, showing them in operative position, Fig. 2 is a vertical sectional view partly in elevation, Fig. 3 is a perspective view of the base plate forming a part of the lock, Fig. 4 is a section taken on the plane of line 4—4 of Fig. 2, and Fig. 5 is a vertical section taken on the plane of line 5—5 of Fig. 2.

Referring in detail to the drawings by numerals, 1 designates generally, a preferably rectangular base plate which is formed upon its inner side with a central circular recess 2, and a groove 3 adjacent the perimeter thereof. A casing, generally designated 4, comprising a front wall 5, top wall 6, bottom wall 7, and side walls 8, is positioned over the base plate 1. The inner edge of the casing is formed with a continuous rib 9 which seats within the groove 3 formed in

the base, and the side walls of the casing are formed with apertured lugs 10 through which fastening screws 11 extend. The lugs engage the vertical edges of the base plate and coöperate with the rib 9 and groove 3 to hold said plate in operative relation with respect to the casing.

A horizontal shaft 12 is journaled within openings 13 and 14 formed in the base and front wall 5 respectively and has rigidly secured thereto a drum or cylinder 15. This shaft may be rotated by means of a handle 16 secured to the forward end thereof. The periphery of the cylinder carries a plurality of pins 17 which are adapted to extend through registering openings formed adjacent the ends of the seal 19. This seal is preferably made of a flexible strip of metal and extends through an opening 20 formed in the top wall 6 of the casing. A plate 21 is secured to the periphery of the cylinder by means of the spring hinge 22 and is adapted to overlap the ends of the seal and hold them against the periphery of the cylinder.

To hold the cylinder against rotation in one direction I employ a ratchet wheel 23, rigid with the shaft 12 and housed within the recess 2; and a spring pawl 24 secured in the peripheral wall of said recess which engages the ratchet teeth.

When it is desired to place a seal in position so that the hasp 25 may not be disconnected from the staple 26 without detection, the seal is run through the staple 90 and its ends brought together so as to bring the opening 18 into registration. Then the ends of the seal are placed in the casing through the slot 20 and the foremost pin 17 inserted through the first pair of openings 18. The cylinder is then rotated in a clockwise direction and carries the ends of the seal and the pins out of reach, as shown in Fig. 4. When a person having the proper authority desires to disconnect the hasp 100 from the staple, the seal is broken and the drum rotated so as to bring the ends opposite the opening 20 so that they may be disconnected from the cylinder and removed, to leave the lock ready to receive another 105 seal. The plate 21 prevents the seal dropping from engagement with the cylinder as the latter is being rotated after the seal has been broken.

From the foregoing description taken in 110

connection with the accompanying drawings, it will be seen that I have provided a very simple and practical seal lock and seal which will make it impossible to open a door to which it is applied without breaking the seal. These seals may be stamped serially so that a broken seal may not be replaced by a new one without danger of detection.

10 While I have shown and described the preferred embodiment of my invention, it will be understood that minor changes in construction, combination and arrangement of parts may be made without departing 15 from the scope and spirit of the invention as claimed.

Having thus described my invention, I claim:—

1. In a seal lock, a casing having an opening formed therein, a cylinder rotatable within the casing, means for holding the cylinder against rotation in one direction, a plurality of pins carried by the periphery of the cylinder, a seal strip inserted through 20 said opening and formed with a plurality of apertures to receive the pins, and a spring 25 pressed plate hinged to the periphery of the cylinder to engage the ends of the strip and

hold said strip against the periphery of the cylinder.

2. In a seal lock, a base plate formed in its inner side with a central circular recess, a casing having a front wall and side walls secured to the base plate around the recess formed therein, a shaft journaled through 30 the casing and base plate, a ratchet wheel rigidly secured to said shaft and seated in the circular recess, a spring pawl fixed to the periphery of the recess and engaging the ratchet wheel, a cylinder rigidly secured 35 to the shaft, a plurality of pins carried by the periphery of the cylinder, one side wall of the casing being formed with an opening, a seal strip inserted through said opening having a plurality of apertures to receive 40 the pins and means carried by the periphery of the cylinder for engagement with the end of the seal strip to hold said strip in engagement with the cylinder periphery.

45 In testimony whereof I affix my signature 50 in presence of two witnesses.

PRESLEY B. JOHNSON.
